UNITED STATES PATENT OFFICE.

HERMON O. WITHERELL, OF ELKHART, INDIANA, ASSIGNOR TO THE EAGLE
KNITTING COMPANY, OF SAME PLACE.

MITTEN.

SPECIFICATION forming part of Letters Patent No. 258,337, dated May 23, 1882.

Application filed March 1, 1882. (No model.)

To all whom it may concern:

Be it known that I, HERMON O. WITHERELL, a citizen of the United States, residing at Elkhart, in the county of Elkhart and State of Indiana, have invented certain new and useful Improvements in Mittens, of which the following is a specification.

My invention relates to the improvement of mittens made of knitted fabric, and in particular does it relate to that class of such mittens which have the hand and wrist portion made two-ply or double, and which are designed to be faced with leather, cloth, or other suitable material.

15 The object of my invention is to provide mittens of knitted fabric which can be readily and cheaply made, which shall at the same time be warm and serviceable, and which shall not be liable while in use to slip from the hands of the wearer. This object of my invention I accomplish by the following method of manufacture:

The outsides of the mittens are knit as a continuous web or tube upon what is commonly known as a "one and one rib machine." The parts of the web or tube which are to form the wrist portions are made narrower than the body or hand portions; and in order that a double thickness may be given to these 30 wrist portions the contracted parts of the web or tube are knit twice the required length of the finished wrist portions, so that so much as may be necessary may be folded inward. To the upper edge of the inner fold of the two-ply wrist I attach, by looping or otherwise, the lining previously knit in a plain continuous web, with thumb-stall integral therewith. The thumb-stall of this lining projects through a suitable opening cut for such purpose in the 40 body of the mitten, the raw edges of such opening being fastened down around the same by stitching or in any other suitable way, and the thumb-stall, when thus formed of a single thickness, covered in the usual manner, while warm, is not clumsy or unwieldy, as is the case where a two-ply covered thumb-stall is made. The upper edges of the body and lining are now to be trimmed to the desired length and shape and to be fastened by looping, stitching, or 50 otherwise, and a facing of leather, cloth, or

other suitable material is to be applied to the mittens in the usual manner.

It is to be noted that by constructing the wrist portion of the mitten in the manner described it will not only be very warm, but also, 55 being highly elastic, will fit snugly to the wrist of the wearer, and thus effectually serve to retain the mitten upon the hand.

Referring now to the accompanying drawings, forming part of this specification, Figure 6c 1 represents a front or palm view of my improved mitten, the usual facing being removed and the double wrist portion being unfolded for the purpose of better illustration. Fig. 2 represents a back view of my mitten with facing attached, a portion being broken away and a portion turned back. Fig. 3 represents a longitudinal sectional view of the two-ply wrist portion of the mitten with a lining applied.

A designates the body or hand portion, integral with which is formed, as above described, the wrist portion, consisting of the contracted elastic folds B and B', one within the other. To the upper edge of the fold B' 70 the lining C is attached, having the thumb-stall D formed thereon to be covered by the portion D' of the facing E. As stated above, the upper ends of the body A and of the lining D are suitably fastened together, and the facing E is attached to the body A in the usual manner.

Having thus described my invention, what I claim as new, and desire to secure by Letters Patent, is—

1. A mitten composed of a hand portion provided with a thumb-opening cut therein, a double contracted wrist portion formed integral with said hand portion, and an attached lining provided with a thumb-stall, substantially as described.

2. A knitted mitten formed from a continuous web and having a whipped or stitched end and a double contracted wrist portion, and provided with an attached lining and facing, substantially as described.

HERMON O. WITHERELL.
